Joseph Horzick, West Chicago, Ill., assignor to Motorola,
Inc., Franklin Park, Ill., a corporation of Illinois

Filed Mar. 22, 1965, Ser. No. 84,385

Term of patent 7 years

(Cl. D56—4)

FIG. 1 is a front perspective view of a television receiver cabinet showing my new design;

FIG. 2 is a top plan view thereof to a reduced scale;

FIG. 3 is a left side elevational view thereof to the same scale as FIG. 2, the right side being substantially a mirror image thereof;

FIG. 4 is a rear elevational view thereof to the same scale as FIG. 2; and

FIG. 5 is a bottom view thereof to the same scale as FIG. 2.

The dominant features of my new design are shown by means of solid lines in the drawing.

I claim:

The ornamental design for a television receiver cabinet, as shown and described.
